[57] **ABSTRACT**

A process for preparing 3-alkyl-5-t-butylphenols which comprises contacting 3-alkyl-6-t-butylphenols with aluminum chloride at a temperature below 70°C whereby the t-butyl group at the 6-position is rearranged to the 5-position to give 3-alkyl-5-t-butylphenols in excellent yields.

**PROCESS FOR PREPARING
3-ALKYL-5-T-BUTYLPHENOLS**

The present invention relates to a process for preparing 3-alkyl-5-t-butylphenols. More particularly, it is concerned with a process for preparing 3-alkyl-5-t-butylphenols in high yields which comprises contacting 3-alkyl-6-t-butylphenols with aluminum chloride under a mild condition to rearrange the t-butyl group at the 6-position to the 5-position, the alkyl being an alkyl having 1 to 3 carbon atoms.

For alkylation of m-cresol, there has heretofore been adopted a procedure where it is reacted with an alkylating agent such as an alkanol, an olefin or an alkyl halide in the presence of a catalyst such as a strong acid or a Friedel-Crafts type catalyst. In this procedure, an alkyl group is selectively introduced into the o- or p-position of the phenolic OH group on the benzene ring and the introduction of an alkyl group into the m-position hardly takes place. Thus, the industrial production of 3-alkyl-5-t-butylphenols in a single step by the utilization of the said procedure is hardly possible.

On the other hand, it is known that m-alkylphenols can be produced by heating the corresponding o- or p-alkylphenols above 125°C in the presence of a strong acid and a natural or synthetic alumina-silicate to rearrange the alkyl group at the o- or p-position to the m-position [U.S. Pat. No. 3,014,079]. When this procedure is applied to 3-alkyl-6-t-butylphenols, however, the elimination of the t-butyl group preferentially takes place rather than the rearrangement of the t-butyl group so that 3-alkyl-5-t-butylphenols are obtained only in trace.

As the results of the extensive study, it has now been found that the treatment of 3-alkyl-6-t-butylphenols with aluminum chloride under a mild condition affords 3-alkyl-5-t-butylphenols in excellent yields. In this connection, it should be noted that the above rearrangement is quite specific to 3-alkyl-6-t-butylphenols and not applicable to any other similar or analogous compound. For instance, the application to 3-methyl-6-isopropylphenol or 3-methyl-6-ethylphenol results only in the recovery of the starting compound without the proceeding of the rearrangement. Further, for instance, the application to o-t-butylphenol gives p-t-butylphenol in a high yield with no material production of the corresponding m-isomer. The application to 2-t-butyl-4-methylphenol results in the elimination of the t-butyl group to give p-cresol. In case of the application to 3-methyl-4-t-butylphenol, the rearrangement of the t-butyl group to the m-position does not take place. The present invention is based on the said finding.

According to the present invention, 3-alkyl-6-t-butylphenols are treated with aluminum chloride at a temperature below 70°C, preferably of 0° to 30°C while stirring for 2 to 4 hours at atmospheric pressure whereby the rearrangement of the t-butyl group at the 6-position to the 5-position takes place to give 3-alkyl-5-t-butylphenols. The amount of aluminum chloride to be used may be 0.25 to 2 mol, preferably 1 mol, per mol of the starting phenol.

The thus obtained 3-alkyl-5-t-butylphenols are utilizable as intermediates in the production of various per se useful substances. For instance, the reaction with methyl isocyanate affords 3-alkyl-5-t-butylphenol N-methylcarbamates, which are insecticides exerting a

strong controlling activity against various harmful insects without any toxicity to mammals.

Practical and presently preferred embodiments of the present invention are illustratively shown in the following Examples.

EXAMPLE 1

To 3-methyl-6-t-butylphenol (30 g) maintained at 30°C, powdery anhydrous aluminum chloride (26 g) is portionwise added. After the addition of aluminum chloride is completed, the resultant mixture is stirred at 20° to 30°C for 2 hours. Then, water (100 ml) is added quickly to the reaction mixture for decomposition of the aluminum complex, whereby black oily material is obtained. The produced oily material is fractionally distilled to give 3-methyl-5-t-butylphenol as a fraction boiling at 100° to 103°C/2.5 mmHg.

The oily product before fractional distillation is confirmed to have the following composition by gas chromatography:

Material	Percent (%)
(I) m-Cresol	21.0
(II) Unidentified component (1)	2.3
(III) Unidentified component (2)	0.9
(IV) 3-Methyl-5-t-butylphenol	67.0
(V) High boiling component	8.8

Elementary analysis of the distilled fraction ((IV)): Calculated (for $C_{11}H_{16}O$): C, 80.42 %, H, 9.84 %. Found: C, 80.62 %; H, 9.58 %.

EXAMPLE 2

3-Methyl-6-t-butylphenol (30 g) and powdery anhydrous aluminum chloride (7 g) are reacted in the same manner as in Example 1. The produced oily material is fractionally distilled to give 3-methyl-5-t-butylphenol as a fraction boiling at 100° to 104°C/2.5 mmHg.

The oily product before fractional distillation is confirmed to have the following composition by gas chromatography:

Material	Percent (%)
(I) m-Cresol	35.2
(II) Unidentified component (1)	8.7
(III) Unidentified component (2)	0.5
(IV) 3-Methyl-5-t-butylphenol	48.3
(V) High boiling component	7.3

Elementary analysis of the distilled fraction (IV): Calculated (for $C_{11}H_{16}O$): C, 80.42 %; H, 9.84 %. Found: C, 80.77 %; H, 9.60 %.

EXAMPLE 3

3-Ethyl-6-t-butylphenol (44 g) and powdery anhydrous aluminum chloride (26 g) are reacted in the same manner as in Example 1. The produced oily material is fractionally distilled to give 3-ethyl-5-t-butylphenol as a fraction boiling at 125° to 129°C/1.8 mmHg.

The oily product before fractional distillation is confirmed to have the following composition by gas chromatography:

Material	Percent (%)
(I) 3-Ethylphenol	36.3
(II) Unidentified component (1)	4.8
(III) Unidentified component (2)	0.2
(IV) Unidentified component (3)	0.2
(V) 3-Ethyl-5-t-butylphenol	31.5
(VI) High boiling component	27.0

Elementary analysis of the distilled fraction (V): Calculated (for $C_{12}H_{18}O$): C, 80.83 %; H, 10.20 %. Found: C, 81.22 %; H, 10.12 %.

EXAMPLE 4

3-Isopropyl-6-t-butylphenol (58 g) and powdery anhydrous aluminum chloride (26 g) are reacted in the same manner as in Example 1. The produced oily material is fractionally distilled to give 3-isopropyl-5-t-butylphenol as a fraction boiling at 130° to $134^{\circ}C/1.8$ mmHg.

The oily product before fractional distillation is confirmed to have the following composition by gas chromatography:

Material	Percent (%)

5		4
(I)	3-Isopropylphenol	31.5
(II)	Unidentified component (1)	1.8
(III)	Unidentified component (2)	0.3
(IV)	Unidentified component (3)	0.3
(V)	3-Isopropyl-5-t-butylphenol	25.6
(VI)	High boiling component	40.5

Elementary analysis of the distilled fraction (V): Calculated (for $C_{13}H_{20}O$): C, 81.18 %, H, 10.50 %. Found: C, 81.66 %; H, 10.05 %.

What is claimed is:

1. A process for preparing a 3-alkyl-5-t-butylphenol which comprises contacting a 3-alkyl-6-t-butylphenol with aluminum chloride at a temperature between about 0° and $30^{\circ}C$ to rearrange the t-butyl group at the 6-position to the 5-position, the alkyl group having 1 to 3 carbon atoms.
2. The process according to claim 1, wherein the aluminum chloride is anhydrous.
3. The process according to claim 1, wherein the contact is effected using a 0.25 to 2 molar amount of aluminum chloride per one molar amount of the 3-alkyl-6-t-butylphenol.
4. The process according to claim 1, wherein the contact is effected for 2 to 4 hours.
